United States Patent Office

Des. 196,706
Patented Oct. 29, 1963

196,706

BRUSH

Robert F. Hannan, Loudonville, N.Y., assignor to Mohawk Brush Company, Albany, N.Y., a corporation of New York

Filed Dec. 17, 1962, Ser. No. 72,885

Term of patent 14 years

(Cl. D9—2)

Fig. 1.

Fig. 2.

Fig. 3.

Fig. 4.

Fig. 5.

FIGURE 1 is a side elevation of a brush, showing my new design;

I claim:

The ornamental design for a brush, as shown.
